UNITED STATES PATENT OFFICE.

ELIJAH B. BROOKSHIRE, OF ELDORADO, KANSAS, ASSIGNOR OF ONE-HALF TO H. H. FAULDERS, OF ELDORADO, KANSAS.

WRENCH.

1,373,296.

Specification of Letters Patent. Patented Mar. 29, 1921.

Application filed January 28, 1920. Serial No. 354,668.

To all whom it may concern:

Be it known that I, ELIJAH B. BROOKSHIRE, a citizen of the United States, residing at Eldorado, in the county of Butler and State of Kansas, have invented certain new and useful Improvements in Wrenches, of which the following is a specification.

The invention relates to wrenches, and more particularly to the class of eccentric operating mechanism for wrenches, vises or the like.

The primary object of the invention is the provision of a wrench of this character, wherein the movable jaw operated directly from a lever constituting the handle of the wrench through the intermediary of an eccentric, or an equivalent structure, the eccentric being mounted on the lever in a novel manner, so as to avoid any possible binding of the jaw when adjusted and also to eliminate play of said movable jaw, while accurate adjustment can be had relative to the work.

Another object of the invention is the provision of a wrench of this character, wherein the movable jaw is fitted within the body thereof in a novel manner so as to be guided toward the stationary jaw, which is an integral part of the body and also to relieve excessive strain upon the pivots supporting the eccentric for operating the movable jaw and also the connection of the lever with the body of the wrench.

A further object of the invention is the provision of a wrench of this character, wherein the operating lever constituting the handle thereof is formed with a forked arm or extension adapted to straddle the slide carrying the movable jaw so that the structure will be equalized and distributed to both sides of the slide carrying the movable jaw and also the eccentric will be maintained in axial alignment with said slide, whereby its movement will be uniform, without any possibility of binding action, yet the said movable jaw will be perfectly free for positive and accurate adjustment in the use of the wrench.

A still further object of the invention is the provision of a wrench of this character which is comparatively simple in construction, novel in form, thoroughly reliable and

efficient in its purpose, strong, durable, and inexpensive to manufacture.

With these and other objects in view, the invention consists in the features of construction, combination and arrangement of parts, as will be hereinafter fully described, illustrated in the accompanying drawing and pointed out in the claims hereunto appended.

In the accompanying drawing:

Figure 1 is a side elevation of a wrench constructed in accordance with the invention.

Fig. 2 is a fragmentary vertical sectional elevation thereof, the slide and the movable jaw being shown in elevation.

Fig. 3 is a view similar to Fig. 2 showing the slide lever and movable jaw in section.

Fig. 4 is an edge elevation of the wrench.

Fig. 5 is a sectional view on the line 5—5 of Fig. 2 looking in the direction of the arrow.

Fig. 6 is a view similar to Fig. 3 showing a slight modification of the eccentric.

Similar reference characters indicate corresponding parts throughout the several views in the drawing.

Referring to the drawings in detail there is shown a wrench construction, it being understood of course that this invention is not limited to the same, as it may be employed in connection with vises or other tools simulating the same and wrenches. The wrench construction comprises a body or head 10 which is cut into from one end and side to provide a stationary jaw 11 and formed transversely through said body or head adjacent to the jaw 11 is a way 12 in which is fitted a slide 13 having formed thereon at right angles to the same a jaw 14 which constitutes the movable jaw to cooperate with the stationary jaw 11 in the use of the wrench.

Formed in the body or head 10 and opening into the way 12 is a cavity or recess 15 for accommodating the pivotally supported portion 16 of a curved operating lever 17 which constitutes the handle of the wrench. The portion 16 has passed transversely therethrough centrally of the same, a threadless bolt 18 which is riveted or otherwise secured

in the opposite cheek 19 of the body or head 10 and in this manner the lever 17 is pivotally connected to the latter.

The ends of the walls of the cavity 15 next to the way 12 in the body or head 10 have formed thereon guide ribs 20, while the slide 13 is formed with a groove or channel 21 for receiving said ribs 20 in the movement of the slide transversely through the body 10, thus it being seen that the said slide is prevented from lateral play or displacement and is positively guided in its movement.

The portion 16 of the lever 17 is formed with a forked extension or arm 22 adapted to straddle the slide 13, the limbs of the fork or associated part of said extension or arm 22 being fitted in notches 23 formed in opposite sides of the slide 13 provided adjacent to one end of the latter and intersecting these notches is a circular opening receiving a correspondingly shaped eccentric roller 24 which is eccentrically supported upon a pivot 25 mounted in the limbs of the associated portion of the extension or arm 22, thus it being seen that the outer faces of the limbs of said forked extension 22 will be flush with the outer faces of the slide 13 due to the fitting of said limbs of the forked extension or arm in the notches 23 in the slide and in this manner eliminating any interference with the free movement of the slide in the way 12 in said body or head of the wrench.

The portions of the cheek 19 of the body or head 10 constituting the walls of the way 12 are provided with transversely alining holes or openings 26 which are located at the extreme limit of the opening throat of the extension or arm 22 for retracting the movable jaw away from the stationary jaw of the wrench so that access may be had to the pivot 25 to enable the easy removal thereof when the occasion requires and also to permit the introduction of the pivot in the assembling of the parts of the wrench.

In Fig. 6 of the drawing there is shown a slight modification of the invention, wherein the slide 13 has formed therein a squared recess 27 for accommodating a slidable block 28 in substitute for the eccentric roller 24, the block 28 being supported upon the pivot

29 for the mounting thereof in the forked portion of the arm or extension or the operating lever of the wrench.

From the foregoing it is thought that the construction and manner of operation of the wrench will be clearly understood and therefore a more extended explanation has been omitted.

What is claimed is:

1. In a wrench of the class described having a head terminating in a stationary jaw and a guide way formed at right angles to said jaw in said head, said guide way comprising side walls and a lower rib, a complementary movable jaw member comprising a shank movable in said guide way and having a lower edge engaging said lower rib, said shank being prevented from lateral movement by said side walls, a lever pivotally mounted between the side walls of said head and terminating in a forked extension seated within curved notches on opposite sides of said shank, a cut out portion in said shank, a cam pivotally mounted between the forked extensions of said lever and bearing in the said cut out portion of the shank whereby the movable jaw is operated to grip and release the work, and a registering opening in the walls of said head for assembling the wrench.

2. In a wrench of the class described having a head terminating in a stationary jaw and a guide way formed at right angles to said jaw in said head, said guide way having side walls, a complementary movable jaw member comprising a shank movable in said guide way and between the walls and prevented from lateral movement thereby, a lever pivotally mounted between the side walls of said head and terminating in a forked extension seated within curved notches on opposite sides of said shank, a cut out portion in said shank, a cam pivotally mounted between the forked extension of said lever and bearing in said cut out portion of the shank whereby the movable jaw is operated to open and close the wrench and a registering opening in the walls of said head for assembling the wrench.

In testimony whereof I affix my signature hereto.

ELIJAH B. BROOKSHIRE.
